DESIGN FOR A JACK

Edward M. Pfauser, Elm Grove, Wis., assignor to
Blackhawk Mfg. Co., Milwaukee, Wis., a cor-
poration of Wisconsin

Application February 27, 1937, Serial No. 67,907

Term of patent 7 years

To all whom it may concern:

Be it known that I, Edward M. Pfauser, a citizen of the United States and a resident of Elm Grove, in the county of Waukesha and State of Wisconsin, have invented a new, original, and ornamental Design for a Jack, of which the following is a specification, reference being had to the accompanying drawing forming a part thereof.

Figure 1 is a perspective view of the jack of the present design showing the lifting arm in lowered position;

Figure 2 is a corresponding view of the jack showing the lifting arm in raised position.

The dominant feature of my design resides in the configuration of the support and enclosure for each rear caster wheel.

I claim:

The ornamental design for a jack, as shown and described.

EDWARD M. PFAUSER.
